(57) CLAIM

The ornamental design for men's undergarment, as shown and described.

DESCRIPTION

FIG. 1 is a top view of a men's undergarment showing my new design.

FIG. 2 is a left side view thereof.

FIG. 3 is a front view thereof.

FIG. 4 is a right side view thereof.

FIG. 5 is a rear view thereof; and,

FIG. 6 is a top isometric view thereof.

In the drawings, the cross-hatched regions indicate stitched seams.

1 Claim, 2 Drawing Sheets
